VENDING MACHINE

Clare E. Hodgman, Mamaroneck, N. Y., assignor to The Coca-Cola Company, New York, N. Y., a corporation of Delaware

Application February 21, 1955, Serial No. 34,594

Term of patent 14 years

(Cl. D52—3)

The figure is a view in perspective of a vending machine, embodying my new design.

The opposite side of the vending machine is substantially the same in appearance as the side shown, and the rear is unadorned.

I claim:

The ornamental design for a vending machine, as shown and described.
